United States Patent Office.

SAMUEL R. DUMMER, OF NEW YORK, N. Y.

Letters Patent No. 71,861, dated December 10, 1867.

CALENDAR-ATTACHMENT TO INKSTANDS.

The Schedule referred to in these Letters Patent and making part of the same.

TO ALL WHOM IT MAY CONCERN:

Be it known that I, S. R. DUMMER, of the city, county, and State of New York, have invented a new and improved Calendar-Attachment to Inkstands, &c.; and I do hereby declare that the following is a full, clear, and exact description thereof, which will enable others skilled in the art to make and use the same, reference being had to the accompanying drawings, forming part of this specification.

The present invention consists, first, in so constructing the body of an inkstand, &c., as to receive and support one above another, but independently of each other, a series of rings or frames, that they can be turned or moved around thereon, on which rings are painted, or otherwise suitably indicated, any data desired, such as, for instance, the names of the calendar months, days of the week, and of the month from 1st to 31st inclusive, in regular order and succession in each case, in combination with a frame or band secured to the outside of the inkstand, &c., which frame is provided with openings at suitable points, to expose to view only one portion or part of the data contained in the said rings, and thus enable, by properly setting the rings opposite such openings, the day of the week and month, together with the name of the month to be indicated therein, for reference or for being read, as from time to time may be desired.

The invention also consists in a novel construction of the inkstand, by which the ink contained in it can be forced up through a tube for being used.

In the accompanying plate of drawings, my improved calendar-attachment for inkstands, &c., together with the new construction for inkstands embraced in the present invention, is illustrated—

Figure 1 being a side view of an inkstand, with the calendar-attachment.

Figure 2, a central vertical section, taken in the plane of the line $x\ x$, fig. 1; and

Figure 3, a horizontal section, taken in the plane of the line $y\ y$, fig. 1.

Similar letters of reference indicate corresponding parts.

A, in the drawings, represents the body of an inkstand, around which is formed a series of parallel rests, or shoulders, B, one above the other, and at equal distances or widths from each other. C, a series of rings, of a width equal to that between the shoulders B of the inkstand, on which they rest, one to each shoulder, and each of sufficient circumference to loosely embrace the circumference of the portions of the inkstand corresponding thereto. The lower one of these rings, G, is marked from the 1st to 31st inclusive, at equal and regular distances apart, the ring next above with the names of the months in regular order and succession, from January to December inclusive, and the upper one of the series with the names of the days of the week, from Sunday to Saturday inclusive, and in regular order and succession. D, a frame or plate, secured to outside of inkstand over rings C, which plate extends down the front of the inkstand from top to bottom. In this plate D is a series of openings, E, corresponding in number and position to the rings C, these openings being of such size as to only expose through them to view one only of each part of the data embraced and indicated in each of the rings.

From the above description, it is plainly obvious that by properly adjusting the rings C, which move independently of each other, any day of the week, together with the month and day of the month, can be readily indicated and exposed for reference, as may be desired.

In addition to the improvement above described, the inkstand is provided with a central vertical tube, H, of a funnel or cup-shape at its outer end, I, where the ink is removed by the pen for use, and also with another tube, M, that extends nearly to the bottom of the inkstand at one side from its side central tube, which tube is provided with a piston or plunger, O. In this tube, M, if the inkstand be tipped to the opposite side while being filled, an air-cushion will be formed when the inkstand is righted in position, so that, by then pushing down the piston, the air-cushion below, being compressed, forces the ink up through the central tube to its cup-shaped end ready for use, when, by lifting up or partially withdrawing said plunger, the ink can be made to flow back into the stand, as is obvious without any further explanation.

I claim as new, and desire to secure by Letters Patent—

1. An inkstand, &c., constructed with a series of shoulders or rests, B, whether one or more, and one above another, in combination with the rings C and plate or frame D, or their respective equivalents, substantially as and for the purpose described.

2. In combination with the above, I claim the two tubes H M and plunger O, as herein set forth for the purpose specified.

The above specification of my invention signed by me, this 27th day of February, 1867.

SAM'L. R. DUMMER.
